UNITED STATES PATENT OFFICE.

WILLIAM FLOSS AND JOHN FLOSS, OF MEADOW LANDS, PENNSYLVANIA.

ELEVATOR SAFETY DEVICE.

SPECIFICATION forming part of Letters Patent No. 742,621, dated October 27, 1903.

Application filed August 10, 1903. Serial No. 168,928. (No model.)

To all whom it may concern:

Be it known that we, WILLIAM FLOSS and JOHN FLOSS, citizens of the United States of America, residing at Meadow Lands, in the county of Washington and State of Pennsylvania, have invented certain new and useful Improvements in Elevator Safety Devices, of which the following is a specification, reference being had therein to the accompanying drawings.

This invention relates to certain new and useful improvements in safety devices for elevators; and the primary object of the invention is to provide means whereby in event of the elevator rope or cable being broken the elevator-cage will be automatically locked and held in the elevator-well and prevented from dropping to the bottom thereof.

Briefly described, the invention comprises a pair of pointed sprag-bars pivoted in a clevis or carrier supported at the top of the elevator-cage, and this clevis or carrier is under the tension of a spring which is normally held compressed whereby to hold the pointed end of the sprag-bars out of engagement with the slide-rails by the weight of the car on the suspending rope or cable. Upon this rope or cable breaking the spring immediately acts to force the sprag-bars into engagement with the slide-rails. Means is also provided whereby these sprag-bars may be manually forced into engagement with the slide-rails to check the movement of the car or cage at any desired time.

In describing the invention in detail, reference is had to the accompanying drawings, forming a part of this specification, and wherein like numerals of reference indicate like parts throughout the several views, in which—

Figure 1 is a central vertical sectional view of the elevator-cage, showing a part of the slide-rails with our improved device in position. Fig. 2 is a top plan view showing the slide-rails in cross-section. Fig. 3 is a sectional view of a part of the cage, showing the clevis or carrier for the sprag-bars. Fig. 4 is a sectional view of one of the slide-rails and elevator-cage, also showing a part of one of the sprag-bars.

To put our invention into practice, we provide a cage 1 with the cross-piece 2, cut away at its ends to form the runways to receive

the slide-rails 3, arranged at opposite sides of the elevator-well. These slide-rails are usually of metal, and in our construction we 55 groove the inner face of the same and place therein a strip of wood 4, the outer face of which is flush with the outer face of the rail 3. In the cross-bar 2, at the top of the elevator-cage, is a recess 5, and in this recess is 60 arranged a stiff coil-spring 6, which is mounted on the rod or stem 7. This rod or stem 7 has a suspending cord or cable 8 of the elevator car or cage attached thereto, and at its lower end the rod or stem is affixed to the carrier 65 or clevis 9, in which is pivotally mounted the sprag-bars 10. These bars have pointed ends 11, which project through openings 12, provided therefor in the side walls 14 of the cage and are adapted to engage, when operated, with the wooden strip 4, placed in the rails 3. The sprag-bars are held normally out of engagement with the rails by the weight of the car or cage on the suspending 70 rope or cable 8, this weight compressing 75 spring 6 and pulling upward the carrier or clevis 9. The sprag-bars are supported intermediate their ends by cables 15, attached to eyes 16 on the sprag-bars and passed over rollers 17, carried by the cross bar or head 2, 80 these cables being passed around the pulleys 18, mounted on top of the elevator-cage, and then connected together, and a second rope or cable 19 passes over the pulley 20. This rope or cable then passes downwardly through 85 the opening 21 and attached to the lever 22, pivoted to the side of the cage 1 at a point convenient to be grasped by the operator.

In case of the rope or cable 8 breaking it will be observed that spring 6 exerts its tension against the carrier or clevis 9, forcing the ends of the sprag-bars into engagement with the wooden strip 4, this strip being prevented from splitting by reason of being set in the metal rails 3. If for any cause the 90 spring 6 should fail to actuate the sprag-bars 10 or if the operator should desire at any time to lock the car, the lever 22 is pulled downwardly, thus causing the rope 19 and ropes or cables 15 to pull upwardly on the outer 95 ends of the sprag-bars and draw the same into engagement with the slide-rails.

It will be noted that various changes may be made in the details of construction without

departing from the general spirit of our invention.

Having fully described our invention, what we claim as new, and desire to secure by Letters Patent, is—

In a safety device for elevators of the type set forth, an elevator-cage provided with openings in the sides thereof, a carrier supported by the suspending - rope of the car, a cross-piece mounted at the top of the cage, means carried therebyto depress the carrier on breaking of the rope, sprag-bars pivotally mounted in the carrier having their outer ends extending into the openings of the cage, a pair of cables centrally supporting the bars, rotatable means carried at opposite sides of the sus-

pending - rope to receive said cables, oppositely-disposed guide-pulleys carried by the cage - top receiving said cables between the same, a rotatable means carried adjacent the same, a cable passing over said means secured to the ends of the first-named cables and extending into the car, and a lever within the car for operating manually said sprag-bars, substantially as described.

In testimony whereof we affix our signatures in the presence of two witnesses.

WILLIAM FLOSS.
JOHN FLOSS.
